UNITED STATES PATENT OFFICE.

CHARLES C. HASKELL, OF BOURNEDALE, MASSACHUSETTS.

TROUSERS-GUARD.

No. 866,276.

Specification of Letters Patent.

Patented Sept. 17, 1907.

Application filed April 17, 1907. Serial No. 368,644.

To all whom it may concern:

Be it known that I, CHARLES C. HASKELL, a citizen of the United States of America, and a resident of Bourndale, in the county of Barnstable and State of Massachusetts, have invented certain new and useful Improvements in Trousers-Guards, of which the following is a specification.

This invention relates to trousers guards and has for its object the production of a suitable guard which is adapted to hold the trousers folded about the legs of the wearer and which is provided with a means forming a part of the trousers guard for preventing the same from working up on the legs of the wearer.

A further object of the invention is to provide such a device which may be readily coiled into a small compass so that it may be conveniently carried in the pocket of the wearer when not in use.

It consists in certain novel features of construction and arrangement of parts which will be readily understood by reference to the description of the drawings and to the claims hereinafter given.

Of the drawings: Figure 1 represents a plan view of the device locked in a coil as when not in operation. Fig. 2 represents an elevation of the same. Fig. 3 represents a perspective view of the same uncoiled and in position for use. Fig. 4 represents a section showing the locking device for the free ends of the leg band and holding ribbon, and Fig. 5 represents a section of the leg band showing the end of the holding ribbon pivoted thereto.

Similar characters designate like parts throughout the several figures of the drawings.

In the drawings, 10 represents a suitable band of metal adapted to be wrapped around the leg of a pair of trousers when folded about the leg of the wearer, one end of the band being provided with a suitable stud or button 11 while the opposite end is provided with a plurality of stud-engaging slots 12 adapted to engage said stud or button 11 to hold the band 10 in position about the leg. The band 10 is made of spring metal which is adapted normally to assume a circular form of smaller diameter than the leg to which it is to be applied. Owing to the spring of metal of which the band 10 is formed this band will hug snugly against the trousers and retain the same in position when folded about the leg even without the use of securing devices at either end thereof. The securing devices, however, are provided to prevent the band from expanding and slipping up on the leg of the wearer. In order to provide an additional means for accomplishing this object the band 10 has pivoted thereto at 13 a ribbon of metal 14 which is adapted to pass under the foot of the wearer and be secured by means of the stud-engaging slots 15 in its free end to the button or stud 11 on the opposite

side of said band 10. This provides a very convenient device which may be used in stormy weather to hold the trouser legs securely wrapped around the leg of the wearer to prevent snow or cold air from entering the interior of the trousers either when traveling afoot in the snow or when driving in the winter. It is especially adapted also for bicycle or horseback riders to retain the trouser legs in their proper position and prevent them from slipping up out of place and exposing the lower part of the leg to the cold.

When not desired for use the ribbon 14 may be moved about the pivot 13 into the same plane with the band 10 and coiled into the position shown in Figs. 1 and 2 at which time the outer stud-engaging slot 15 may be made to engage the stud or button 16 to securely lock the band and ribbon in position. In order to better accomplish this the ribbon 14 is provided at 17 with a hole through which the stud or button 11 is adapted to pass when in this coiled position.

This makes a very convenient form of trousers guard which is cheaply constructed, easily carried in the pocket of the wearer, and which may be quickly placed in position upon the wearer when its use is desired.

The operation of the invention and its many advantages will be thoroughly apparent without further description.

Having thus described my invention, I claim:

1. A trousers-guard consisting of a band of metal provided at the ends with suitable devices adapted to lock the ends together; and a ribbon pivoted at one end to said band and provided at its free end with means whereby it may be locked to said band. 85

2. A trousers-guard consisting of a band of metal provided at the ends with suitable devices adapted to lock the ends together; and a ribbon pivoted at one end to said band and provided at its free end with means whereby it may be locked to said band and also provided with means for locking said band and ribbon in a coil when not in operation. 90

3. A trousers-guard consisting of a band of metal having in one end thereof a stud-engaging slot and having at its other end a stud adapted to engage said slot; and a ribbon secured at one end to said band and provided at the other with a stud-engaging slot adapted to engage said stud. 95

4. A trousers-guard consisting of a band of metal having in one end thereof a plurality of stud-engaging slots and having at its other end a stud adapted to engage one of said slots; and a ribbon pivoted at one end to said band and provided at the end with a stud-engaging slot adapted to engage said stud. 100

5. A trousers-guard consisting of a band of metal having in one end thereof a plurality of stud-engaging slots and having at its other end a stud adapted to engage one of said slots; and a ribbon of metal secured at one end to said band and provided at the other with a stud-engaging slot adapted to engage said stud. 105

6. A trousers-guard consisting of a band of metal having in one end thereof a plurality of stud-engaging slots and having at its other end a stud adapted to engage one of said slots; and a ribbon of metal pivoted at one end to

said band and provided at the other with a plurality of stud-engaging slots either of which is adapted to engage said stud.

7. A trousers-guard consisting of a band of metal having at one end thereof a stud-engaging slot and having at its other end a stud adapted to engage said slot; and a ribbon of metal pivoted at one end to said band and provided at the other with a stud-engaging slot adapted to engage said stud, said ribbon having intermediate its ends another stud

adapted to engage the ribbon slot to hold said band and 10 ribbon in a coil when not in use.

Signed by me at Sandwich Massachusetts this thirteenth day of April A. D. 1907.

CHARLES C. HASKELL.
